INDEX PAD HOLDER

Morton M. Rodbell, New York, N. Y.

Application December 31, 1947, Serial No. 143,474

Term of patent 14 years

(Cl. D74—1)

To all whom it may concern:

Be it known that I, Morton M. Rodbell, a citizen of the United States, residing at New York, in the county of New York and State of New York, have invented a new, original, and ornamental Design for an Index Pad Holder as shown in the enclosed drawings, in which:

The side not shown is substantially the same as the side shown.

I claim:

The ornamental design for an index pad holder, as shown and described.

MORTON M. RODBELL.
